MEANS FOR USE IN THE MANUFACTURE
OF SHOESArthur F. Pym, Swampscott, Mass., assignor to
United Shoe Machinery Corporation, Paterson,
N. J., a corporation of New Jersey

Application September 8, 1931, Serial No. 561,612

95 Claims. (Cl. 12—14)

This invention relates to means for use in the manufacture of shoes, and in some of its aspects has more particular reference to means for use in lasting shoes. Objects of the invention are to provide improved means for holding shoe uppers in lasted position, and also to provide in a lasting machine mechanism for use in applying such upper-holding means to a shoe. The invention has further in view the provision of means for holding an insole in proper relation to a last and for effectively supporting a lip or rib on the insole against pressure in the lasting operation. Still another object is to provide improved means for positioning a last and shoe in proper relation to means that operates on the shoe.

With the above and other objects in view, there is herein disclosed, in one important aspect of the invention, a novel construction and arrangement of means for holding the marginal portion of an upper in lasted position until conditions are such that it will maintain that position without the aid of extraneous holding or fastening means. The construction shown comprises a member constructed for attachment to the last and shoe upon the bottom face of the insole prior to the lasting operation, a device for engaging and holding the upper, and means to render the insole-engaging member effective to maintain the upper-holding device in operative position. More particularly, as illustrated, the insole-engaging member comprises a plate adapted to be fastened on the insole by tacks and having thereon a screw-threaded projection provided with a nut which by turning movement is effective to transmit force from the plate to the upper-holding device to press the device toward the bottom face of the last, the nut acting thereafter to hold the device clamped down upon the shoe bottom. It is to be understood, however, that the invention is not limited to means of that particular character for controlling the upper-holding device. The construction disclosed is especially designed for use in lasting the toe ends of shoes of a type in which the marginal portion of the upper is lasted against an insole lip or rib (hereinafter termed the lip), the upper-holding device comprising a member curved to engage the upper around the toe in the angle between the feather and the lip of the insole and flexible to permit it to be pressed inwardly toward the lip at the sides of the toe by the wipers of a lasting machine; and it is contemplated that such means will be advantageously used to hold the upper until box-toe-stiffening material has hardened sufficiently to maintain the toe portion of the upper in lasted position.

It will, however, be readily recognized that the invention is likewise applicable to the lasting of portions of shoes other than the toe ends and to the lasting of shoes other than those having lipped insoles, for example those in which the margin of the upper is lasted in parallel relation to the bottom face of the last; and that upper-holding means of the character disclosed may be advantageously used in the manufacture of shoes in which the uppers are fastened in lasted position by cement.

As hereinabove suggested, it is a further object of the invention to hold an insole in proper relation to the last and if the insole is provided with a lip, to support the lip against pressure in the lasting operation. In the construction shown this purpose is served by the above-mentioned member or plate that is fastened upon the toe-end portion of the insole, this plate being shaped to fit the inner face of the insole lip all around the toe and to support the lip substantially throughout its height against the pressure of the lasting wipers while also maintaining the toe portion of the insole close to the bottom face of the last. This permits the upstanding margin of the upper to be pressed very firmly against the lip by the wipers without danger of distorting the lip. As illustrated, moreover, the lip-supporting member cooperates with the upper-holding member in clamping the margin of the upper and the lip firmly together.

For positioning the last and shoe in proper relation to means that operates on the shoe, in accordance with another object of the invention, further use is made, in the construction shown, of the plate above referred to as fastened on the insole, this plate having thereon positioning surfaces arranged to cooperate with corresponding positioning surfaces on a shoe machine, herein shown as a toe-lasting machine, to determine the position of the last and shoe in the machine. As herein disclosed, these positioning surfaces are so formed and arranged as to determine the position of the work heightwise, lengthwise and laterally and also in respect to any swinging or tipping movements, so that its proper position is in all respects determined without any special care on the operator's part. It will be evident that, as illustrated, the position of the above-mentioned plate on the shoe is determined by engagement with the toe-end portion of the lip of the insole, and that by the means disclosed this portion of the lip is accordingly positioned in exactly the right relation to the toe-embracing wipers of the lasting machine.

whereby the margin of the upper is pressed against the lip.

Still further to accomplish the objects in view, the invention provides in a lasting machine novel means for applying to a shoe a device for holding the upper in lasted position. For use in applying about the upstanding marginal portion of the toe end of an upper a device such as hereinafter described, the construction shown comprises means for moving the device both heightwise of the shoe and lengthwise thereof independently of the toe wipers, together with means for controlling the device in such manner as to cause it properly to embrace the upstanding margin of the upper about the toe and thereafter to press and hold the upper firmly and evenly all around the toe in lasted relation to the insole.

The above and other features of the invention, including various novel details of construction and combinations of parts, will now be more particularly described by reference to the accompanying drawings and pointed out in the claims.

In the drawings,

Fig. 1 is a view in front elevation of a portion of a lasting machine in which novel features of the invention are embodied, showing the machine in the act of applying to the toe of a shoe an upper-holding device constructed in accordance with the invention;

Fig. 2 is a plan view on a smaller scale of a portion of the structure shown in Fig. 1;

Fig. 3 is a view on a larger scale, partly in front elevation and partly in vertical section, showing in greater detail the means for holding the upper, for controlling the insole and for positioning the last and shoe, and also the means for applying the upper-holding device to the shoe;

Fig. 4 is a view similar to Fig. 3 of a portion of the structure there shown, illustrating the positions of the parts after the upper-holding device has been fastened in operative position;

Fig. 5 is a perspective view of the forepart of the shoe with the insole-engaging plate thereon, showing also the upper-holding device detached from the shoe;

Fig. 6 is a perspective view of a portion of the means for applying the upper-holding device, showing also that device mounted thereon; and

Fig. 7 is a perspective view of a portion of the work-positioning means.

The means herein shown for holding the marginal portion of the toe end of an upper in lasted relation to the lip *a* of an insole on a last comprises an upper-holding device adapted to be applied to the shoe after the toe-end portion of the upper has been wiped into lasted position, as by the toe-embracing wipers 3 of the illustrated lasting machine, and also a member fastened to the insole and last and provided with means for maintaining the upper-holding device in operative position. The upper-holding device in the form illustrated comprises an upper-engaging member 10 and a plate 12 on which this member is supported. The member 10 consists of a substantially U-shaped metal band adapted to be positioned with an edge thereof toward the bottom face of the last and to embrace the upstanding marginal portion of the upper lasted against the lip of the insole around the toe. The band is flexible to adapt it to be pressed inwardly toward the insole lip at the sides of the toe, and is also resilient, its construction being such that its opposite ends normally occupy positions some-

what nearer together than when it is applied in holding relation to the upper so that by its resiliency it tends to press the upper at the sides of the toe toward the lip of the insole. The intermediate portion of the member 10 is fastened to the plate 12 by a screw 14. At its opposite ends the member 10 is provided with inturned flanges 16 having therein slots 18 through which extend screws 20 that are threaded in the plate 12, the heads of these screws overlapping the flanges 16. The screws 20 thus hold the end portions of the member 10 close to the plate 12 while permitting these portions to be moved toward and from each other. The screws further serve to limit inward and outward movements of the end portions of the member.

The member above referred to as fastened to the insole and last comprises a plate 22 so formed as to overlie the toe-end portion of the insole and substantially to fit the inner face of the lip *a* of the insole all around the toe. The plate 22 is provided with a plurality of openings 24 to receive tacks *t* driven through the insole into the last in such manner as to clamp the plate down upon the shoe bottom. A comparatively large number of such openings are provided, only a few of which are utilized to fasten the plate on any particular shoe, the arrangement being such that the tacks needed to fasten the plate may be driven through different openings in operating on different shoes so as to avoid always driving the tacks in the same places in the last. Preferably, as illustrated, the openings 24 are so formed that different tacks will be inclined in such relation to each other as to assist by such inclinations in holding the plate firmly down on the insole. The plate 22 has a downwardly projecting marginal portion 26 arranged to engage the insole in the channel at the inner side of the lip and is so formed as to engage and support the lip substantially throughout the height of the latter, the plate being further so constructed that its intermediate portion is upraised somewhat above the bottom face of the insole, as illustrated in Figs. 3 and 4.

To render the plate 22, fastened to the last and insole as above described, effective to maintain the upper-holding device in operative position, there is provided on the plate a screw-threaded projection 28 on which is mounted a nut 30 arranged to overlap the upper face of the plate 12 of the upper-holding device. It will be evident that by turning the nut 30 after the upper-holding device has been applied to the shoe this device may be clamped in upper-holding position and may even be forced toward the bottom face of the last with greater pressure, and that the nut serves thereafter to transmit force from the plate 22 to the upper-holding device to hold the device pressed firmly against the upper toward the bottom face of the last until such time as it is desired to remove the upper-holding means from the shoe.

It will be understood that the plate 22 will be fastened to the last and insole in the manner described prior to the toe-lasting operation. In addition to maintaining the upper-holding device in operative position the plate has the further important function of supporting the lip of the insole against the pressure applied by the wipers 3 in wiping the upper inwardly against the outer face of the lip. This permits the upstanding marginal portion of the upper materials to be pressed very firmly against the lip by the wipers without any danger of distorting the lip,

so that the upper materials are conformed very closely to the angle between the feather and the lip of the insole before the upper-holding device is applied. The plate 22 serves further to hold the insole close to the bottom face of the last all around the toe near the edge of the last bottom, which greatly facilitates the wiping of the upper tightly over the extreme edge of the insole by the wipers.

10 In the use of machines for lasting the toe ends of shoes by means of toe-embracing wipers it is important that the toe wipers and the toe-end portion of each last and shoe be positioned in such relation to each other that the wipers in their operation will wipe the upper close to the end and side faces of the last and to the edge of the insole and will also wipe it tightly inward over the insole and press it firmly upon the margin of the insole all around the toe. In lasting shoes having lipped insoles it is also important that the wipers press the marginal portion of the upper closely against the lip of the insole at the end and the sides of the toe. With these considerations in view, the present invention further provides simple and effective means for properly positioning each last and shoe in the machine without the necessity for any special care on the operator's part. For this purpose the plate 22, which bears a definite relation to the bottom face of the insole and is also positioned on the shoe as determined by the lip of the insole, is provided with a plurality of positioning surfaces formed and arranged to cooperate with corresponding positioning surfaces provided on the lasting machine to determine the position of the last and shoe in the machine. One of these positioning surfaces is a plane surface 32 formed on the upper face of the plate and arranged to engage a corresponding surface 34 (Fig. 7) formed on the lower face of a plate 36 which is fast on an arm 38 mounted in a fixed position on the frame of the machine. It will be evident that these cooperating surfaces determine the position of the last and shoe in respect to height and in respect to any tipping movements and accordingly determine the plane in which the feather of the insole at its toe end is presented. An upward projection 40 on the plate 22 is further provided with opposite side surfaces 42, one of which is shown in Fig. 5, and with an end surface 44 arranged to cooperate with corresponding surfaces provided by a slot 46 (Fig. 7) in the plate 36. These cooperating surfaces determine the position of the last and shoe in respect to lengthwise and lateral bodily movements and in respect to lateral swinging movements. It will accordingly be evident that the position of the last and shoe in respect to movements in all directions is determined by the positioning surfaces formed respectively on the plate 22 and on the plate 36 of the lasting machine. It will be understood that the insole will have been fastened as usual on the bottom of the last with the edge of its toe-end portion flush with the edge of the toe-end portion of the last bottom, and since the position of the plate 22, as hereinbefore explained, is determined by the lip of the insole, the plate will bear the same relation to the edge of the insole and the end and side faces of the last in operating on all shoes of the same size and style. After the toe wipers, therefore, have been properly adjusted to operate on a shoe of a given size and style, no further adjustment will be required in operating on other shoes of the same size

and style, and all that the operator will need to do in presenting each last and shoe to the machine will be to bring the plate 22 to the position predetermined by the plate 34. After each shoe has thus been presented, a toe rest 48 is raised into supporting relation to the last and shoe, as illustrated. The means for operating this toe rest and also features of the wiper-operating and controlling mechanism in the machine herein shown are substantially as disclosed in Letters Patent No. 1,918,274, granted on July 18, 1933 upon an application of F. N. LaChapelle and F. C. Eastman, and need not be described in detail. For an understanding of the present invention it is sufficient to state that the wipers are advanced and closed by means of a hand lever 50 (Fig. 1) and that the wipers, together with various mechanisms for operating and adjusting them, are carried by a support 52 which is vertically movable by means of a double-acting treadle 54 connected by a rod 56 to a slide 58 on which the support 52 is mounted.

For applying to the shoe the upper-holding device hereinbefore described there is pivotally mounted at 60 on a bracket 62, which is supported on the vertically movable toe-wiper mechanism, a lever 64 arranged to extend lengthwise of the shoe over the shoe bottom. Throughout a portion of its length this lever is divided to provide two spaced members 66, and adjacent to the lower faces of these members there is mounted a plate 68 provided with upstanding flanges 70 adjacent to the outer side faces of the members 66, these flanges carrying pins 72 mounted in slots 74 extending lengthwise of the lever 64 in the members 66. The plate 68 is thus slidable lengthwise of the lever 64 while being maintained in parallel relation to the lower faces of the members 66 by the pins 72. Lugs 76 projecting downwardly from the plate 68 carry pins 78 on which are pivotally mounted lugs 80 projecting upwardly from a plate 82 which is constructed and arranged to serve as a carrier for the upper-holding device. This device, preparatory to its application to the shoe, is mounted on the carrier plate 82 in a position determined by pins 84 on the carrier plate which are arranged to enter holes 86 (Fig. 5) formed in the plate 12 of the upper-holding device. To support the device in the position determined by these pins there are pivotally mounted on the above-mentioned pins 78 latches 88 the ends of which are arranged to project under the plate 12, as illustrated in Fig. 6, when the latches are in the positions there shown. These latches serve additionally, by engagement with the opposite end portions of the flexible resilient band 10, to maintain these portions farther apart than when they are in upper-holding positions.

The carrier 82 for the upper-holding device is further controlled by means that positions it initially in an inclined relation to the lever 64 such that when this lever is lowered that portion of the member 10 that engages the upper at the end of the toe is carried first into contact with the wipers 8 while the portions that engage the upper at the sides of the toe are still somewhat above the wipers, the member being thus presented in inclined relation to the shoe bottom. This controlling means comprises a rod 90 having fast on its lower end a block 92 pivotally connected by a pin 94 to lugs 96 on the plate 82, this rod extending upwardly through a tubular member 98 which is fast on the plate 68 and serves as a housing for a spring 100 bearing 150

downwardly against the block 92. The rod 90 extends loosely through the upper end of the member 98 and has threaded on its upper end a nut 102 which by engagement with the member 98 limits downward movement of the rod and accordingly determines the initial position of the carrier plate 82 with respect to swinging movement about the pins 78. A stop screw 104 in the block 92 is arranged to engage the lower face of the plate 68 to limit the relative movement of this plate and the carrier plate 82 against the resistance of the spring 100. For moving the plate 68 and the parts supported thereon lengthwise of the lever 64 there is provided a lever 106 (Fig. 2) pivotally mounted on a bracket 108 which is fast on one of the members 66, the lever being connected to the plate 68 in a forked extension of the latter by means of a pin 110 carried by the plate and extending through a slot in the lever.

In the use of the above-described mechanism for applying the upper-holding device to the shoe the device is first mounted on the carrier 82 in the position determined by the pins 84, and the latches 88 are swung into positions to support the device on the carrier, as illustrated in Fig. 6, the ends of these latches being positioned against the inner faces of the end portions of the band 10 which are moved apart by the operator far enough to admit the ends of the latches. It will be understood that at this time the lever 64 occupies a different position from that indicated in the drawings to permit the upper-holding device to be readily mounted as described. Before applying the device to the shoe the operator will have wiped the marginal portion of the toe end of the upper into lasted position against the lip of the insole by means of the wipers 8, as illustrated in Fig. 3, using the lever 50 to advance and close the wipers and using the treadle 54 to move them heightwise of the toe to upwipe the upper around the toe and thereafter to move them downwardly to press the upper forcibly against the feather of the insole. With the wipers in the position indicated in Fig. 3 the operator swings the lever 64 downwardly over the shoe, and by reason of the fact that the carrier plate 82 is positioned at that time by the spring 100 in inclined relation to the lever, the edge of the intermediate portion of the upper-holding member 10 is first carried into contact with the upper faces of the wipers. By means of the lever 106, which the operator controls simultaneously with the lever 64, the plate 68 is so positioned that the member 10 first engages the wipers as described a little in front of the gathered marginal portion of the upper materials at the end of the toe. The operator then, by means of the lever 106, moves the upper-holding device along the wipers while at the same time bearing down on the lever 64 enough to insure that the edge of the member 10 will slide down the beveled upper surface of the wipers near the wiping edges until the member is pressed against the upstanding margin of the upper projecting above the wipers at the end of the toe. The lever 64 having then been moved downwardly far enough to position the member 10 close to the wipers at the sides of the toe, the operator swings the latches 88 out of their operative positions and thus releases the ends of the member 10 which by the resiliency of the member spring inwardly against the margin of the upper at the sides of the toe and press it against the lip of the insole. The lever 64 is then further depressed to insure that the edge of the member 10 will be pressed

firmly against the wipers adjacent to their edges all around the toe, as illustrated in Fig. 3, the spring 100 at that time having yielded to such an extent that the stop screw 104 engages the plate 68. While maintaining the downward pressure on the lever 64 the operator backs off the wipers 8 enough to admit the lower edge of the member 10 between the edges of the wipers and the upstanding margin of the upper, the member being pressed downwardly to this position by the lever 64, as illustrated in Fig. 4. It will be evident that before the wipers 8 are backed off the member 10 is positioned and held as described in such relation to the margin of the upper as to insure against any loosening of the upper by the retractive movement of the wipers. It will be understood that the stop screw 104 is so adjusted that when the member 10 is in the position illustrated in Fig. 4 it is pressed positively down by the lever 64 with the lower edge of the member in parallel relation to the plane of the lower faces of the wipers and in firm engagement with the upper all around the toe. With the parts in these positions the wipers may be advanced and closed by the lever 50 to press the member 10 more firmly inward toward the lip of the insole at the end and the sides of the toe. By the use of a suitable tool the operator then turns the nut 30 into clamping relation to the plate 12 so that the nut presses and holds the member 10 firmly down on the shoe bottom. The lever 64 is then lifted, the pins 84 being withdrawn from the holes 86 in the plate 12. Thereafter the wipers are retracted and the shoe with the upper-holding means thereon is removed from the machine. It will be understood that this means will be left on the shoe until the box-toe-stiffening material has hardened sufficiently to maintain the toe-end portion of the upper in lasted position without extraneous holding means. Thereafter the nut 30 will be loosened, the upper-holding device removed and the plate 22 also detached from the shoe by prying it upwardly from the shoe bottom.

While the invention is thus herein illustrated as applied to the manufacture of shoes of a type 120 in which the upper is lasted against a lip on an insole, it will be understood that in various novel aspects it is likewise applicable to the manufacture of shoes of other kinds, for example those in which the margin of the upper is lasted substantially flat upon the outer face of the insole and in which the upper is secured in lasted position by cement; and further that it is not limited to the lasting of the toe ends of shoes. It will also be understood that various novel features disclosed are not limited to machines of the particular type herein shown.

Having described the invention, what I claim as new and desire to secure by Letters Patent of the United States is:—

1. Means for holding the marginal portion of an upper in lasted position over the bottom of a last, comprising a member constructed for temporary attachment to the bottom of the last, a device for applying holding pressure to the marginal portion of the upper toward the bottom face of the last, and means movable relatively to said member after its attachment to the last to transmit force from the member to said device in a direction heightwise of the last.
2. Means for holding the marginal portion of an upper in lasted position over the bottom of a last, comprising a member constructed for temporary attachment to the bottom of the last, a device for applying holding pressure to the mar-

- ginal portion of the upper toward the bottom face of the last, and a member mounted for turning movement relatively to said first-named member after its attachment to the last to transmit force from the attached member to said device in a direction heightwise of the last. 5
3. Means for holding the marginal portion of an upper in lasted position over the bottom of a last, comprising a member constructed for temporary attachment to the bottom of the last, a device for applying holding pressure to the marginal portion of the upper over the bottom of the last, and means for transmitting force from said member to the upper-holding device comprising a screw-threaded member movable to press said device upon the upper toward the bottom face of the last. 10
4. Means for holding the marginal portion of an upper in lasted position over the bottom of a last, comprising a member constructed for temporary attachment to the bottom of the last, a device for applying holding pressure to the marginal portion of the upper over the bottom of the last, and screw-threaded means mounted on said member for movement to clamp said device on the upper toward the bottom face of the last. 15
5. Means for holding the marginal portion of an upper in lasted position over the bottom of a last, comprising a member constructed for temporary attachment to the bottom of the last, a device for applying holding pressure to the marginal portion of the upper over the bottom of the last, said member having a screw-threaded projection thereon, and a nut threaded on said projection for movement to clamp said device in upper-holding position. 20
6. Means for holding the marginal portion of an upper in lasted position over the bottom of a last, comprising a member constructed for temporary attachment to the bottom of the last, another member for applying holding pressure to the marginal portion of the upper over the bottom of the last, and a device mounted on one of said members for turning movement in cooperation with the other member to press said upper-holding member upon the upper toward the bottom face of the last. 25
7. Means for holding the marginal portion of an upper in lasted position over the bottom of a last, comprising a member constructed for attachment to the bottom of the last by tacks, another member for applying holding pressure to the marginal portion of the upper toward the bottom face of the last, and a device movable after the attachment of said first-named member to the last to render said attached member effective to press the upper-holding member toward the bottom face of the last. 30
8. Means for holding the marginal portion of an upper in lasted relation to an insole on a last, comprising a member constructed for attachment to the last and shoe upon the bottom face of the insole, a device for applying holding pressure to the marginal portion of the upper upon the insole, and means movable relatively to said member after its attachment to the last and shoe to render the member effective to hold said device upon the upper with force directed toward the bottom face of the last. 35
9. Means for holding the marginal portion of an upper in lasted relation to an insole on a last, comprising a member constructed for attachment to the last and shoe upon the bottom face of the insole, a device constructed to hold the marginal portion of the upper upon the insole, and a mem- 40
- ber mounted for turning movement relatively to said first-named member to render the latter effective to hold said device pressed upon the upper toward the bottom face of the last. 45
10. Means for holding the marginal portion of an upper in lasted relation to an insole on a last, comprising a member adapted to be positioned upon the bottom face of the insole and having one or more openings therein for fastenings driven through the insole into the last to attach it to the insole and last, a device constructed for holding engagement with the marginal portion of the upper upon the insole, and means movable to render said member effective to maintain said device in upper-holding position with force directed toward the bottom face of the last. 50
11. Means for holding the marginal portion of an upper in lasted relation to an insole on a last, comprising a plate adapted to be positioned upon the bottom face of the insole prior to the lasting operation and constructed for attachment to the last through the insole, a device constructed for holding engagement with the marginal portion of the upper upon the insole, and means movably supported on said plate for pressing said device down upon the upper. 55
12. Means for holding the marginal portion of an upper in lasted relation to an insole on a last, comprising a plate adapted to be positioned upon the bottom face of the insole prior to the lasting operation and having openings therein to receive fastenings for attaching it to the insole and last, a device constructed to hold the marginal portion of the upper upon the insole, and screw-threaded means movable to transmit force from the plate to said device after the plate has been thus attached to the last to maintain the device in pressure-applying relation to the upper. 60
13. Means for holding the marginal portion of an upper in lasted relation to an insole on a last, comprising a plate adapted to be positioned upon the bottom face of the insole and having openings therein to receive fastenings for attaching it to the insole and last, a device constructed for holding engagement with the marginal portion of the upper upon the insole, said plate having a screw-threaded projection thereon, and a nut threaded on said projection for clamping said device upon the upper. 65
14. Means for holding the marginal portion of an upper in lasted relation to an insole on a last, comprising a member constructed for attachment to the last and shoe upon the bottom face of the insole prior to the lasting operation, and means constructed and arranged to cooperate with said member to hold the marginal portion of the upper pressed toward the bottom face of the last by engagement with the outer face of the upper. 70
15. Means for holding the marginal portion of an upper in lasted relation to an insole on a last, comprising a member constructed for attachment to the last and shoe upon the bottom face of the insole prior to the lasting operation, and means constructed and arranged to cooperate with said member to hold the marginal portion of the upper in lasted relation to the insole by engagement with the outer face of the upper and movable relatively to the member to press the upper upon the insole in a direction heightwise of the last. 75
16. Means for holding the marginal portion of an upper in lasted relation to an insole on a last, comprising a member constructed for attachment to the last and shoe upon the bottom face of the insole prior to the lasting operation, a device constructed for holding engagement with the 80

- marginal portion of the upper upon the insole, and screw-threaded means movable in cooperation with said member to press said device upon the upper.
17. Means for holding the marginal portion of an end of an upper in lasted relation to an insole on a last, comprising a member constructed for attachment to the last and shoe upon an end portion of the insole and adapted to hold the insole close to the bottom of the last, a device having a portion curved in approximate conformity to the curvature of the edge of the end of the shoe bottom for applying holding pressure to the upper, and means movable relatively to said member after its attachment to the last and shoe to render the member effective to hold said device upon the upper with force directed heightwise of the last. 80
18. Means for holding the marginal portion of an end of an upper in lasted relation to an insole on a last, comprising a member portable with the last and shoe in clamping engagement with an end of the insole, another member curved in approximate conformity to the curvature of the edge of the end of the shoe bottom for holding engagement with the marginal portion of the upper, and means movably mounted on one of said members and arranged to cooperate with the other member to hold said upper-engaging member upon the upper with force directed heightwise of the last. 85
19. Means for holding the marginal portion of an end of an upper in lasted relation to an insole on a last, comprising a member portable with the last and shoe in clamping engagement with an end of the insole, said member having a screw-threaded portion, a device curved in approximate conformity to the curvature of the edge of the end of the shoe bottom for holding engagement with the upper, and a screw-threaded member arranged to cooperate with the screw-threaded portion of said insole-clamping member to hold said device upon the upper. 90
20. Means for holding the marginal portion of an end of an upper in lasted position over an insole on a last, comprising a plate adapted to be tacked upon the bottom face of an end of the insole and having a screw-threaded projection thereon, a device having a portion curved in approximate conformity to the curvature of the edge of the end of the shoe bottom for holding engagement with the upper, and a nut threaded on said projection for pressing said device down on the upper. 100
21. Means for holding the marginal portion of an end of an upper in lasted position over an insole on a last, comprising a member portable with the last and shoe upon an end of the insole, a device constructed for holding engagement with the marginal portion of the upper around the end thereof and having portions movable relatively to each other laterally of the shoe in applying it to the shoe, and means movably mounted on said member for pressing said device upon the upper toward the bottom face of the last. 105
22. Means for holding the marginal portion of an end of an upper in lasted position over an insole on a last, comprising a member constructed for attachment to the last and shoe upon an end of the insole, a device constructed for holding engagement with the marginal portion of the upper around the end thereof and having portions movable relatively to each other laterally of the shoe in applying it to the shoe, and a member mounted for turning movement after the attachment of said first-named member to the last and shoe to render the attached member effective to press said device down upon the upper. 110
23. Means for holding the marginal portion of an end of an upper in lasted position over an insole on a last, comprising a member adapted to be tacked upon an end of the insole, a device constructed for holding engagement with the marginal portion of the upper around the end thereof and having portions movable relatively to each other laterally of the shoe in applying it to the shoe, a plate arranged to overlie said relatively movable portions, and means movable relatively to said member after it has been tacked upon the insole to render the member effective on said plate to press the upper-holding device upon the upper. 115
24. Means for holding the marginal portion of an end of an upper in lasted position over an insole on a last, comprising a member adapted to be tacked upon an end of the insole and having a screw-threaded projection thereon, a device constructed for holding engagement with the marginal portion of the upper around the end thereof and having portions movable relatively to each other laterally of the shoe in applying it to the shoe, a plate arranged to overlie said relatively movable portions, and a nut threaded on said projection for engaging said plate to clamp the upper-holding device upon the upper. 120
25. Means for holding the marginal portion of an end of an upper in lasted position over an insole on a last, comprising a member constructed for attachment to the last and shoe upon the bottom face of an end portion of the insole, a flexible member constructed for holding engagement with the marginal portion of the upper around the end of the shoe bottom and adapted to be flexed laterally of the shoe in applying it to the shoe, and means movable relatively to said first-named member after its attachment to the last and shoe to render it effective to hold said flexible member pressed upon the upper toward the bottom face of the last. 125
26. Means for holding the marginal portion of an end of an upper in lasted position over an insole on a last, comprising a member constructed for attachment to the last and shoe upon the bottom face of an end portion of the insole, a flexible member having a normal curvature approximating that of the edge of the end of the shoe bottom for engaging the marginal portion of the upper over the insole and adapted to be flexed laterally of the shoe in applying it to the shoe, and a member mounted for turning movement after the attachment of said first-named member to the last and shoe to render the attached member effective to press said flexible member upon the upper in a direction heightwise of the last. 130
27. Means for holding the marginal portion of an end of an upper in lasted position over an insole on a last, comprising a member portable with the last and shoe over the bottom face of an end portion of the insole, said member having a screw-threaded projection thereon, a device having a flexible portion adapted to engage the marginal portion of the upper over the insole around the end of the shoe bottom and to be flexed laterally of the shoe in applying it to the shoe, and a nut threaded on said projection for movement to press said device down upon the upper. 135
28. Means for holding the marginal portion of an end of an upper in lasted position over an insole on a last, comprising a member portable with the last and shoe over the bottom face of the last. 140

- an end portion of the insole, a flexible member having a normal curvature approximating that of the edge of the end of the shoe bottom for engaging the marginal portion of the upper over the insole and adapted to be flexed laterally of the shoe in applying it to the shoe, a plate to which said flexible member is attached, and screw-threaded means on said first-named member arranged to act on said plate to hold the flexible member pressed against the upper. 5
29. Means for holding the marginal portion of an end of an upper in lasted position over an insole on a last, comprising a member adapted to be applied over an end of the insole and having openings therein to receive tacks driven through the insole into the last to hold the member on the insole, said member having a screw-threaded projection thereon, a flexible member having a normal curvature approximating that of the edge of the end of the shoe bottom for engaging the marginal portion of the upper over the insole and adapted to be flexed laterally of the shoe in applying it to the shoe, a plate to which said flexible member is attached, and a nut threaded on said projection and arranged to bear on said plate to press the flexible member down upon the upper. 10
30. Means for holding the marginal portion of an end of an upper in lasted position over an insole on a last, comprising a member adapted to be fastened upon the bottom face of an end of the insole prior to the lasting operation, a device constructed for holding engagement with the marginal portion of the upper around the end of the shoe bottom and adapted to be assembled with said member after the wiping of the margin of the upper inwardly over the insole, and means on said member for maintaining said device in upper-holding position. 15
31. Means for holding the marginal portion of an end of an upper in lasted position over an insole on a last, comprising a member adapted to be fastened upon the bottom face of an end of the insole prior to the lasting operation, a device constructed for holding engagement with the marginal portion of the upper around the end of the shoe bottom and adapted to be assembled with said member after the wiping of the margin of the upper inwardly over the insole, and a connection between said member and device for pressing the device upon the upper and maintaining it in upper-holding position. 20
32. Means for holding the marginal portion of an end of an upper in lasted position over an insole on a last, comprising a member adapted to be fastened upon the bottom face of an end of the insole prior to the lasting operation, a device constructed for holding engagement with the marginal portion of the upper around the end of the shoe bottom and adapted to be assembled with said member after the wiping of the margin of the upper inwardly over the insole, and a member mounted for turning movement in cooperation with said first-named member to press said device upon the upper. 25
33. Means for holding the marginal portion of an upper in lasted position against the lip of an insole on a last, comprising members portable with the last and shoe for clamping the upper and lip between them. 30
34. Means for holding the marginal portion of an upper in lasted position against the lip of an insole on a last, comprising a member portable with the last and shoe in engagement with the inner face of the lip, an upper-engaging mem- 35
- ber, and means arranged to cooperate with said lip-engaging member to hold said upper-engaging member against the upper at the outer side of the lip. 80
35. Means for holding the marginal portion of an upper in lasted position against the lip of an insole on a last, comprising a member constructed for attachment to the insole in engagement with the inner face of the lip, a member constructed for holding engagement with the upper in the angle between the feather and the lip of the insole, and means movable relatively to said lip-engaging member to render the latter effective to maintain the upper-engaging member in upper-holding position. 85
36. Means for holding the marginal portion of an upper in lasted position against the lip of an insole on a last, comprising a member constructed for attachment to the last and shoe in engagement with the inner face of the lip, a member for engaging the upper at the outer side of the lip, and a device movable relatively to said lip-engaging member to render the latter effective to hold the upper-engaging member pressed against the upper toward the bottom face of the last. 90
37. Means for holding the marginal portion of an upper in lasted position against the lip of an insole on a last, comprising a member constructed for attachment to the insole in engagement with the inner face of the lip, a member constructed for engagement with the upper in the angle between the feather and the lip of the insole, and a device movably mounted on said lip-engaging member for pressing said upper-engaging member upon the upper toward the bottom face of the last. 95
38. Means for holding the marginal portion of an upper in lasted position against the lip of an insole on a last, comprising a member arranged to engage the inner face of the lip and constructed for attachment to the last and shoe by one or more fastenings penetrating the shoe bottom, a member for engaging the upper at the outer side of the lip, and means arranged to render said lip-engaging member effective to maintain the upper-engaging member in upper-holding position. 100
39. Means for holding the marginal portion of an upper in lasted position against the lip of an insole on a last, comprising a member arranged to engage the inner face of the lip of the insole to support the lip against pressure in the lasting operation, and an upper-engaging member arranged to cooperate with said lip-engaging member to clamp the upper and lip together, said members being portable with the last and shoe. 105
40. Means for holding the marginal portion of an upper in lasted position against the lip of an insole on a last, comprising a member constructed for attachment to the insole in engagement with the inner face of the lip to support the lip against pressure in the lasting operation, another member for engaging the upper in the angle between the feather and the lip of the insole, and screw-threaded means on said first-named member movable to press said upper-engaging member upon the upper. 110
41. Means for holding the marginal portion of an upper in lasted position against the lip of an insole on a last, comprising a member constructed for attachment to the insole in engagement with the inner face of the lip, said member having a screw-threaded projection thereon, a device for engaging the upper in the angle between the feather and the lip of the insole, and a nut 115
- 120
- 125
- 130
- 135
- 140

threaded on said projection for clamping said device against the upper toward the bottom face of the last.

42. Means for holding the marginal portion of the toe end of an upper in lasted position against the lip of an insole on a last, comprising a device formed substantially to fit the inner face of the lip of the insole around the toe, and a device constructed for holding engagement with the upper around the toe at the outer side of the lip, said devices being portable with the last and shoe while clamping the upper and lip between them.

43. Means for holding the marginal portion of the toe end of an upper in lasted position against the lip of an insole on a last, comprising a member formed substantially to fit the inner face of the lip of the insole around the toe and constructed for attachment to the insole and last in engagement with the lip, a device constructed for holding engagement with the upper around the toe at the outer side of the lip, and means to render said member effective to maintain said device in upper-holding position.

44. Means for holding the marginal portion of the toe end of an upper in lasted position against the lip of an insole on a last, comprising a member formed substantially to fit the inner face of the lip of the insole around the toe and constructed for attachment to the insole and last in engagement with the lip, a device constructed for holding engagement with the upper around the toe at the outer side of the lip, and means movable relatively to said member after its attachment to the insole and last to render the member effective to hold the upper-engaging device on the upper.

45. Means for holding the marginal portion of the toe end of an upper in lasted position against the lip of an insole on a last, comprising a member formed substantially to fit the inner face of the lip of the insole around the toe and constructed for attachment to the insole and last in engagement with the lip, a device constructed for holding engagement with the upper around the toe at the outer side of the lip, and means movably mounted on said member for pressing said upper-engaging device on the upper.

46. Means for holding the marginal portion of the toe end of an upper in lasted position against the lip of an insole on a last, comprising a member formed substantially to fit the inner face of the lip of the insole around the toe and constructed for attachment to the insole and last in engagement with the lip, a device constructed for holding engagement with the upper around the toe at the outer side of the lip, and a device mounted for turning movement after the attachment of said member to the insole and last to render the member effective to press the upper-engaging device on the upper toward the bottom face of the last.

47. Means for holding the marginal portion of the toe end of an upper in lasted position against the lip of an insole on a last, comprising a plate formed substantially to fit the inner face of the lip of the insole around the toe and adapted to be fastened to the insole and last by fastenings penetrating the shoe bottom to support the lip in the lasting operation, a device constructed for holding engagement with the upper around the toe at the outer side of the lip, and means for connecting said device to the plate to maintain the device in upper-holding position.

48. Means for holding the marginal portion of

the toe end of an upper in lasted position against the lip of an insole on a last, comprising a plate formed substantially to fit the inner face of the lip of the insole around the toe and adapted to be fastened to the insole and last to support the lip in the lasting operation, said plate having a screw-threaded portion, a device constructed for holding engagement with the upper around the toe at the outer side of the lip, and a screw-threaded member arranged to cooperate with said screw-threaded portion of the plate to maintain the device in upper-holding position.

49. Means for holding the marginal portion of the toe end of an upper in lasted position against the lip of an insole on a last, comprising a plate formed substantially to fit the inner face of the lip of the insole around the toe and adapted to be fastened to the insole and last to support the lip in the lasting operation, a device constructed for holding engagement with the upper around the toe at the outer side of the lip, and a member movably mounted on said plate for pressing said device on the upper toward the bottom face of the last.

50. Means for holding the marginal portion of the toe end of an upper in lasted position against the lip of an insole on a last, comprising a plate formed substantially to fit the inner face of the lip of the insole around the toe and adapted to be fastened to the insole and last to support the lip in the lasting operation, said plate having a screw-threaded projection thereon, a flexible member curved in approximate conformity to the curvature of the toe end of the shoe bottom for engaging the upper around the toe at the outer side of the lip, a plate on which said flexible member is mounted, and a nut threaded on said projection and arranged to bear on said last-named plate to press said flexible member upon the upper and maintain it in upper-holding position.

51. Means for holding the marginal portion of the toe end of an upper in lasted position against the lip of an insole on a last, comprising a device formed to embrace the upstanding margin of the upper positioned against the lip of the insole around the toe, said device having the portions thereof at the sides of the toe under spring control tending to force them inwardly toward the lip of the insole when the device is applied to a shoe.

52. Means for holding the marginal portion of the toe end of an upper in lasted position against the lip of an insole on a last, comprising a flexible resilient member curved to embrace the upstanding margin of the upper around the toe and so constructed as to act by its resiliency to press the margin of the upper inwardly against the lip of the insole at the sides of the toe.

53. Means for holding the marginal portion of an end of an upper in lasted position, comprising a flexible resilient member curved to extend around the end of the shoe bottom for holding engagement with the lasted margin of the upper, the opposite end portions of said member being normally maintained by its resiliency nearer together than when it is in upper-holding position.

54. Means for positioning a shoe and last relatively to means for operating on the shoe, comprising a device portable with the shoe and last over the shoe bottom and having positioning surfaces formed to cooperate with corresponding surfaces of a shoe machine to determine the position of the shoe and last with respect to length-

- wise and lateral bodily movements and lateral swinging movements.
55. Means for positioning a shoe and last relatively to means for operating on the shoe, comprising a device portable with the shoe and last over the shoe bottom and having positioning surfaces formed to cooperate with corresponding surfaces of a shoe machine to determine the position of the shoe and last with respect to movements in all directions. 10
56. Means for positioning a shoe and last relatively to means for operating on the shoe, comprising a device constructed for attachment to the shoe and last by tacks penetrating the shoe bottom and having positioning surfaces formed to cooperate with corresponding surfaces of a shoe machine to position the shoe and last in the machine with respect to movements in different directions. 15
57. Means for positioning a shoe and last relatively to means for operating on the shoe, comprising a device constructed for attachment to the shoe and last by fastenings driven into the shoe bottom and having positioning surfaces formed to cooperate with corresponding positioning surfaces of a shoe machine to determine the position of the shoe and last with respect to lengthwise and lateral bodily movements and lateral swinging movements. 20
58. Means for positioning a shoe and last relatively to means for operating on the shoe, comprising a plate adapted to be positioned upon the bottom face of an insole on the last and having openings therein to receive fastenings driven through the insole into the last to hold the plate in clamping relation to the insole, said plate having thereon positioning surfaces formed to cooperate with corresponding surfaces of a shoe machine to position the shoe and last in the machine. 25
59. Means for positioning a shoe and last relatively to toe-embracing wipers of a lasting machine, comprising a device portable with the shoe and last upon the bottom face of the toe end of an insole on the last, said device having thereon positioning surfaces formed to cooperate with corresponding surfaces on the machine to determine the position of the shoe and last with respect to lengthwise and lateral bodily movements and lateral swinging movements. 30
60. Means for positioning a shoe and last relatively to toe-embracing wipers of a lasting machine, comprising a device portable with the shoe and last upon the toe end of an insole on the last and constructed for attachment to the last by tacks, said device having thereon positioning surfaces formed to cooperate with corresponding surfaces on the machine to determine the position of the shoe and last with respect to movements in all directions. 35
61. Means for positioning a shoe and last relatively to means for operating on the shoe, comprising a device portable with the shoe and last in a position determined by engagement with the lip of an insole on the last, said device being constructed to cooperate with a part of a shoe machine to determine the position of the shoe and last in the machine. 40
62. Means for positioning a shoe and last relatively to means for operating on the shoe, comprising a device portable with the shoe and last in a position determined by engagement with the lip of an insole on the last, said device having thereon positioning surfaces formed to cooperate with corresponding surfaces of a shoe machine 45
- to determine the position of the shoe and last with respect to lengthwise and lateral bodily movements and lateral swinging movements.
63. Means for positioning a shoe and last relatively to means for operating on the shoe, comprising a device adapted to be positioned upon the bottom face of an insole on the last in a location determined by engagement with the lip of the insole and having openings therein to receive fastenings driven through the insole into the last to fasten it in that location, said device being constructed to cooperate with a part of a shoe machine to determine the position of the shoe and last in the machine. 50
64. Means for positioning a shoe and last relatively to toe-embracing wipers of a lasting machine, comprising a device portable with the shoe and last in a position determined by engagement with the toe-end portion of the lip of an insole on the last, said device having thereon positioning surfaces formed to cooperate with corresponding surfaces on the machine to position the shoe and last relatively to the wipers. 55
65. Means for positioning a shoe and last relatively to toe-embracing wipers of a lasting machine, comprising a device formed for engagement with the inner face of the lip of an insole on the last at the end and the sides of the toe to determine its position on the insole and constructed for attachment to the last in that position by fastening means penetrating the insole, said device having thereon positioning surfaces formed to cooperate with corresponding surfaces on the machine to determine the position of the shoe and last relatively to the wipers. 60
66. Means for positioning a shoe and last relatively to toe-embracing wipers of a lasting machine, comprising a device portable with the shoe and last and formed substantially to fit the inner face of the lip of an insole on the last around the toe end of the insole to determine the position of said device on the insole, said device having thereon positioning surfaces formed to cooperate with corresponding surfaces on the machine to determine the position of the shoe and last relatively to the wipers with respect to lengthwise and lateral bodily movements and lateral swinging movements. 65
67. Means for positioning a shoe and last relatively to toe-embracing wipers of a lasting machine, comprising a plate formed substantially to fit the inner face of the lip of an insole on the last around the toe end of the insole and having therein openings to receive fastenings driven through the insole into the last to fasten it in a position determined by the lip, said plate having thereon positioning surfaces formed to cooperate with corresponding surfaces on the machine to determine the position of the shoe and last relatively to the wipers. 70
68. Means for positioning a shoe and last relatively to means in a shoe machine for operating on the shoe, comprising a device portable with the shoe and last over the shoe bottom and having positioning surfaces thereon, and a device on the machine provided with positioning surfaces for engaging said first-named surfaces, the different positioning surfaces being so formed and arranged as to determine the position of the shoe and last with respect to lengthwise and lateral bodily movements and lateral swinging movements. 75
69. Means for positioning a shoe and last relatively to means in a shoe machine for operating on the shoe, comprising a device adapted to be positioned on the bottom face of an insole on the 80

- last and constructed for attachment to the last by tacks penetrating the insole, said device having positioning surfaces thereon, and a device on the machine provided with positioning surfaces for 5 engaging said first-named surfaces, the different positioning surfaces being so formed and arranged as to determine the position of the shoe and last with respect to lengthwise and lateral bodily movements and lateral swinging movements.
- 10 70. Means for positioning a shoe and last relatively to means in a shoe machine for operating on the shoe, comprising a device portable with the shoe and last in a position determined by engagement with the lip of an insole on the last, 15 and a device on the machine constructed and arranged to cooperate with said first-named device to determine the position of the shoe and last relatively to the operating means. 80
71. Means for positioning a shoe and last relatively to means in a shoe machine for operating on the shoe, comprising a device constructed for attachment to the shoe and last in a position determined by engagement with the lip of an insole on the last, said device having positioning 20 surfaces thereon, and a device on the machine constructed for attachment to the shoe and last in a position determined by engagement with the lip of an insole on the last, said device having positioning 25 surfaces thereon, and a device on the machine provided with positioning surfaces to engage said first-named surfaces, the different positioning surfaces being so formed and arranged as to determine the position of the shoe and last with respect to lengthwise and lateral bodily movements and lateral swinging movements. 85
72. Means for positioning a shoe and last relatively to toe-embracing wipers of a lasting machine, comprising a device formed substantially 30 to fit the inner face of the lip of an insole on the last around the toe end of the insole to determine the position of the device on the insole and constructed for attachment to the shoe and last in the position thus determined, said device having 35 positioning surfaces thereon, and a device on the machine having positioning surfaces arranged to engage said first-named surfaces to determine the position of the shoe and last relatively to the wipers. 90
73. Means for positioning a shoe and last relatively to toe-embracing wipers of a lasting machine, comprising a device formed substantially 40 to fit the inner face of the lip of an insole on the last around the toe end of an insole to determine the position of the device on the insole and constructed for attachment to the shoe and last in the position thus determined, said device having 45 positioning surfaces thereon, and a device on the machine having positioning surfaces arranged to engage said first-named surfaces, the different positioning surfaces being formed and arranged to determine the position of the shoe and last with respect to movements in all directions. 95
74. Means for positioning a shoe and last relatively to toe-embracing wipers of a lasting machine, comprising a device formed to engage the inner face of the lip of an insole on the last at the end and sides of the toe to determine the position 50 of the device on the insole and having openings therein to receive tacks for fastening it in the position thus determined, said device having positioning surfaces thereon, and a device on the machine having positioning surfaces arranged to 55 engage said first-named surfaces to determine the position of the shoe and last with respect to lengthwise and lateral bodily movements and lateral swinging movements. 100
75. Means for use in lasting the toes of shoes, comprising a device constructed for attachment 60 to a shoe and last over the toe end of an insole on the last and having thereon positioning surfaces formed to cooperate with corresponding surfaces on a lasting machine to position the shoe and last relatively to toe-embracing wipers, and another device portable with the shoe and last and arranged to cooperate with said first-named device to hold the marginal portion of the upper around the toe in lasted relation to the insole. 105
76. Means for use in lasting the toes of shoes, comprising a device constructed for attachment to a shoe and last over the toe end of an insole on the last and having thereon positioning surfaces formed to cooperate with corresponding surfaces on a lasting machine to position the shoe and last relatively to toe-embracing wipers, another device portable with the shoe and last for holding the marginal portion of the upper around the toe in lasted relation to the insole, and means for rendering said first-named device effective to maintain the upper-holding device in pressure-applying relation to the upper. 110
77. Means for use in lasting the toes of shoes, comprising a device constructed for attachment to a shoe and last over the toe end of an insole on the last and having thereon positioning surfaces formed to cooperate with corresponding surfaces on a lasting machine to position the shoe and last relatively to toe-embracing wipers, another device portable with the shoe and last for holding the marginal portion of the upper around the toe in lasted relation to the insole, and a member movably mounted on said first-named device for pressing said upper-holding device on the upper. 115
78. Means for use in lasting the toes of shoes, comprising a device constructed for attachment to a shoe and last in a position determined by engagement with the toe end of the lip of an insole on the last and having thereon positioning surfaces formed to cooperate with corresponding surfaces on a lasting machine to position the shoe and last relatively to toe-embracing wipers, another device portable with the shoe and last for holding the marginal portion of the upper around the toe in lasted relation to the lip of the insole, and means for rendering said first-named device effective to maintain said upper-holding device in operative position. 120
79. Means for use in lasting the toes of shoes, comprising a device formed substantially to fit the inner face of the lip of an insole on a last around the toe end of the insole to determine the position of the device on the insole and to support the lip against pressure in the lasting operation, said device being constructed for attachment to the shoe and last in the position thus determined and having thereon positioning surfaces formed to cooperate with corresponding surfaces on a lasting machine to position the shoe and last relatively to toe-embracing wipers, another device portable with the shoe and last for holding the marginal portion of the upper around the toe in lasted relation to the lip of the insole, and a member mounted for turning movement and arranged to cooperate with said first-named device to press said upper-holding device upon the upper and to maintain it in operative position. 125
80. In a lasting machine, the combination with lasting means movable to work the marginal portion of an end of an upper into lasted position over the bottom of a last, of a carrier constructed to receive and support a device for temporarily holding the marginal portion of the upper in 130
- 75 comprising a device constructed for attachment 135 to a shoe and last over the toe end of an insole on the last and having thereon positioning surfaces formed to cooperate with corresponding surfaces on a lasting machine to position the shoe and last relatively to toe-embracing wipers, and another device portable with the shoe and last and arranged to cooperate with said first-named device to hold the marginal portion of the upper around the toe in lasted relation to the insole. 140
- 76 80 Means for use in lasting the toes of shoes, comprising a device constructed for attachment to a shoe and last over the toe end of an insole on the last and having thereon positioning surfaces formed to cooperate with corresponding surfaces on a lasting machine to position the shoe and last relatively to toe-embracing wipers, another device portable with the shoe and last for holding the marginal portion of the upper around the toe in lasted relation to the insole, and means for rendering said first-named device effective to maintain the upper-holding device in pressure-applying relation to the upper. 145
- 77 85 Means for use in lasting the toes of shoes, comprising a device constructed for attachment to a shoe and last over the toe end of an insole on the last and having thereon positioning surfaces formed to cooperate with corresponding surfaces on a lasting machine to position the shoe and last relatively to toe-embracing wipers, another device portable with the shoe and last for holding the marginal portion of the upper around the toe in lasted relation to the insole, and a member movably mounted on said first-named device for pressing said upper-holding device on the upper. 150

lasted position around the end of the shoe bottom, said carrier being movable heightwise of the last relatively to said lasting means to press said device upon a portion of the upper previously 5 uncovered by retractive movement of the lasting means toward the edge of the shoe bottom.

81. In a lasting machine, the combination with lasting means for working the marginal portion of an end of an upper into lasted position over 10 the bottom of a last, of a carrier constructed to receive and support a device for temporarily holding the marginal portion of the upper in lasted position around the end of the shoe bottom, said carrier being movable heightwise of the 15 last relatively to said lasting means to press said device on the upper and movable also lengthwise of the last in applying the device to the upper.

82. In a lasting machine, the combination with lasting means for working the marginal portion 20 of an end of an upper into lasted position over the bottom of a last, of a carrier constructed to receive and support a device for temporarily holding the marginal portion of the upper in lasted position around the end of the shoe bottom, 25 and a lever supporting said carrier and movable to press said device against the upper upon the shoe bottom, the carrier being supported on the lever for movement lengthwise of the shoe in applying the device to the shoe.

83. In a lasting machine, the combination with lasting means for working the marginal portion 30 of an end of an upper into lasted position over the bottom of a last, of mechanism constructed to apply to the upper around the end of the shoe bottom after the upper has been worked into 35 lasted position an upper-holding device having upper-engaging portions resiliently movable toward each other laterally of the shoe, said mechanism including means for temporarily holding 40 said upper-engaging portions comparatively wide apart.

84. In a lasting machine, the combination with lasting means for working the marginal portion of an end of an upper into lasted position over 45 the bottom of a last, of a carrier constructed to receive and support an upper-holding device comprising a flexible resilient member curved to extend around the end of the shoe bottom, said carrier being movable to press said member upon 50 the marginal portion of the upper after the upper has been worked into lasted position and being provided with mechanism for engaging the opposite ends of said member to hold them temporarily in positions farther apart than they normally assume by the resiliency of the member.

85. In a lasting machine, the combination with lasting means movable to work the marginal portion of the toe end of an upper into lasted position against the lip of an insole on a last, of 60 mechanism movable heightwise of the last relatively to said lasting means to apply around the upstanding marginal portion of the upper a device for temporarily holding the toe end of the upper in lasted position and to press said device 65 against a portion of the upper previously uncovered by retractive movement of the lasting means toward the edge of the shoe bottom.

86. In a lasting machine, the combination with lasting means for working the marginal portion 70 of the toe end of an upper into lasted position against the lip of an insole on a last, of mechanism for applying around the marginal portion of the upper a device for temporarily holding the toe end of the upper in lasted position, said 75 mechanism comprising means for moving said

device heightwise of the last relatively to the lasting means to press it upon the upper and for also moving it lengthwise of the last to force it against the upstanding margin of the upper at the end of the toe.

87. In a lasting machine, the combination with lasting means for working the marginal portion of the toe end of an upper into lasted position against the lip of an insole on a last, of mechanism for applying around the toe a device for holding the marginal portion of the upper in lasted position, said mechanism comprising a member movable by the operator to force said device against the upper toward the bottom face of the last and another member movable by the operator to force the device lengthwise of the shoe against the upstanding margin of the upper at the end of the toe.

88. In a lasting machine, the combination with lasting means for working the marginal portion of the toe end of an upper into lasted position against the lip of an insole on a last, of a carrier constructed to receive and support a device for holding the marginal portion of the upper around the toe in lasted position, a support for said carrier movable heightwise of the shoe to press the device upon the upper, and means carried by said support for moving the carrier lengthwise of the shoe to force the device against the upstanding margin of the upper at the end of the toe.

89. In a lasting machine, the combination with toe-embracing wipers for wiping the marginal portion of the toe end of an upper into lasted position against the lip of an insole on a last, of mechanism for applying around the toe a device for holding the marginal portion of the upper in lasted position, said mechanism being movable to apply the device in holding relation to the upstanding margin of the upper projecting beyond the wipers while the wipers are holding the upper pressed against the lip of the insole and thereafter to force the device toward the feather of the insole upon retractive movement of the wipers.

90. In a lasting machine, the combination with toe-embracing wipers for wiping the marginal portion of the toe end of an upper into lasted position against the lip of an insole on a last, of mechanism for applying around the toe a device for holding the marginal portion of the upper in lasted position, said mechanism being movable to carry the device first into contact with the outer faces of the wipers while the wipers are holding the upper pressed against the lip of the insole, then to apply it in holding relation to the upstanding margin of the upper projecting beyond the wipers, and thereafter to force it toward the feather of the insole upon retractive movement of the wipers.

91. In a lasting machine, the combination with toe-embracing wipers for wiping the marginal portion of the toe end of an upper into lasted position against the lip of an insole on a last, of a carrier constructed to receive and support a device for holding the marginal portion of the upper around the toe in lasted position, a support for said carrier movable to apply said device first in contact with the outer faces of the wipers while the wipers are holding the upper pressed against the lip of the insole, and means for moving the carrier along its support to apply the device against the upstanding margin of the upper and thus to hold the upper while the wipers are

retracted to permit the device to be forced against the upper on the feather of the insole.

92. In a lasting machine, the combination with toe-embracing wipers for wiping the marginal portion of the toe end of an upper into lasted position against the lip of an insole on a last, of mechanism for applying to the shoe a member curved to embrace and hold the upstanding margin of the upper around the toe, said mechanism being constructed to apply said member first to the margin of the upper at the end of the toe with the member inclined to the shoe bottom and thereafter to seat the member on the upper all around the toe in substantially parallel relation to the shoe bottom.

93. In a lasting machine, the combination with toe-embracing wipers for wiping the marginal portion of the toe end of an upper into lasted position against the lip of an insole on a last, of a carrier constructed to receive and support an upper-holding device comprising a member curved to embrace and hold the upstanding margin of the upper around the toe, and mechanism for moving said carrier heightwise and lengthwise of the shoe to apply said member to the upper, said mechanism including spring-controlled means arranged to tip the carrier to such a position as to cause the member to be applied first to the margin of the upper at the end of the toe and yieldable thereafter to permit the member to be seated on the upper in substantially parallel relation to the shoe bottom all around the toe.

94. In a lasting machine, the combination with

toe-embracing wipers for wiping the marginal portion of the toe end of an upper into lasted position against the lip of an insole on a last, of a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

95. In a lasting machine, the combination with toe-embracing wipers for wiping the marginal portion of the toe end of an upper into lasted position against the lip of an insole on a last, of a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, a spring arranged to control the tipping of the carrier and to position it in inclined relation to the shoe bottom in first applying said device to the shoe, said spring being yieldable as the carrier support is moved toward the shoe bottom, and means arranged to act positively in place of the spring to seat the device firmly on the shoe bottom.

ARTHUR F. PYM.

35. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

40. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

45. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

50. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

55. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

60. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

65. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

70. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.

75. In a lasting machine, the combination with a carrier for applying to the shoe a device for embracing and holding the upstanding margin of the upper around the toe, a support for said carrier movable heightwise of the shoe toward the shoe bottom, the carrier being mounted on its support for limited tipping movement about an axis extending laterally of the shoe, and spring means arranged to maintain the carrier normally at one limit of its tipping movement and to yield in applying said device to the shoe.
